UNITED STATES PATENT OFFICE.

ADELMER M. BATES, OF CHICAGO, ILLINOIS, ASSIGNOR TO BATES VALVE BAG COMPANY, OF CHICAGO, ILLINOIS, A CORPORATION OF WEST VIRGINIA.

BAG-TIE.

1,164,450.

Specification of Letters Patent. Patented Dec. 14, 1915.

Application filed March 14, 1912. Serial No. 683,665.

To all whom it may concern:

Be it known that I, ADELMER M. BATES, a citizen of the United States, residing at Chicago, in the county of Cook and State of Illinois, have invented a certain new and useful Improvement in Bag-Ties, of which the following is a specification.

My invention relates to a tie, particularly such as is applicable to the closure of packages and especially flexible bags.

Its object is to provide a tie which shall contain a minimum length of wire, shall be easily untied or untwisted, shall have no dangerous projecting end portions, shall have convenient means for the attachment of a tag, and shall have other advantages such as are hereinafter pointed out.

One illustration of my invention is set forth in the accompanying drawings, where-
20 in—

Figure 1 is a plan view of a bag with my tie in position for twisting; Fig. 2 is a side elevation of a bag with my tie attached; Fig. 3 is a similar side elevation with the tag attached; Fig. 4 is the side elevation of a bag to which my tie has been attached and from which it has been untied.

Like parts are indicated by the same letters in all the figures.

30 A is a bag and B the crimped end thereof, C is the bent portion of the tie, D the free flexible end preferably having the enlargement E, F is a closed loop forming the other end of the tie and G is the twist. It will be understood, of course, that these illustrations are to be taken as more or less diagrammatic and that the size, proportion and arrangement of the several parts can be greatly varied without departing from the 40 spirit of the invention. The tie is made in the process of tying the package. I shall describe it in connection with the tie of a bag either empty or filled, but it will be understood that the description will apply 45 equally to other devices or packages.

The use and operation of my invention are as follows: A wire, preferably from a spool is preferably upset or provided with a head at its outer end. It is then carried 50 around the crimped portion of the bag and its two parts brought together so as to tightly compress such crimped portion. If a loop is desired, the wire is now severed and bent over so as to form such loop. The 55 inner end of the looper portion should be

approximately at the point where the lower end of the twist of the completed tie is found. This bending over of the wire to form the loop makes a relatively rigid or stout unyielding portion. The two ends, 60 one thus looped and the other free and single and therefore relatively yielding and relatively long, are brought closely together about the bag, preferably without being overlapped, though they may overlap if 65 that is desired. They are then twisted together until as illustrated the two projecting ends consist one of a relatively rigid double base portion and a loop, the other of a long single relatively flexible portion. 70 When now it becomes necessary to untie the bag the long end can be grasped between the thumb and finger and rotated about the short stubby rigid end with a crank-like motion rapidly and easily. There is no pro- 75 jecting end to injure the operator or the fabric of the package because one end is looped and the other is provided with a head. When the tag is to be applied, the long flexible end can be run through the 80 eyelet and then carried back therethrough and attached to the loop as indicated. If no tag is to be applied and no loop is desired, then after the wire has been brought about the crimped end of the bag either before or 85 after the twisting, the wire may be severed at a point where such severed end will be at the top of the twisted portion of the completed tie. This makes such severed end a short end, as compared with the long flex- 90 ible end, with a relatively rigid projecting part so that the long end may be as before grasped between the thumb and finger and by a crank-like motion untwisted from the short stubby rigid end. In either case the 95 untwisting is much easier than where both ends are simultaneously manipulated to affect the untwisting. In the latter case, there is, of course, no projecting end to injure the operator or the fabric.

100 I claim:

1. A bag tie comprising a section adapted to inclose the crimped portion of a bag, a reinforced short section extending beyond said inclosing section at one end and a long, 105 inflexible section extending beyond the inclosing section at the other end, the flexible section twisted around the reinforced section to complete the tie on the bag.

2. A bag tie comprising a section adapted 110

to inclose the crimped portion of a bag, a reinforced short section extending beyond said inclosing section at one end and terminating in a loop, and a long, flexible section extending beyond the inclosing section at the other end, the flexible section twisted around the reinforced section to complete the tie on the bag.

3. A bag tie comprising a section adapted to inclose the crimped portion of a bag, a reinforced short section extending beyond said inclosing section at one end and formed

by twisting one portion of the tie on another, and a long, flexible section extending beyond the inclosing section at the other ¹⁵ end, the flexible section twisted around the reinforced section to complete the tie on the bag.

Signed at Chicago, Illinois, this 2nd day of March, 1912.

ADELMER M. BATES.
